(57) **CLAIM**

The ornamental design for an electronic module, substantially as shown and described.

DESCRIPTION

FIG. 1 is a perspective rear view of a first embodiment of an electronic module.

FIG. 2 is a rear view of the embodiment of FIG. 1.

FIG. 3 is a front view of the embodiment of FIG. 1.

FIG. 4 is a left side view of the embodiment of FIG. 1.

FIG. 5 is a right side view of the embodiment of FIG. 1.

FIG. 6 is a bottom view of the embodiment of FIG. 1.

FIG. 7 is a top view of the embodiment of FIG. 1.

FIG. 8 is a perspective rear view of a second embodiment of an electronic module.

FIG. 9 is a rear view of the embodiment of FIG. 8.

FIG. 10 is a front view of the embodiment of FIG. 8.

FIG. 11 is a left side view of the embodiment of FIG. 8.

FIG. 12 is a right side view of the embodiment of FIG. 8.

FIG. 13 is a bottom view of the embodiment of FIG. 8; and,

FIG. 14 is a top view of the embodiment of FIG. 8.

The claimed design is illustrated in these two examples as a portion of an electronic module, such as a removable module of a handheld electronic device, such as a mobile telephone. The broken lines in each figure illustrate graphical environmental features that form no part of the claimed design.
